US00D443248S

(12) **United States Design Patent**
Sakasegawa

(10) Patent No.: **US D443,248 S**
(45) Date of Patent: ** Jun. 5, 2001

(54) **SIGNAL-INPUT DEVICE**

(75) Inventor: **Takeshi Sakasegawa, Abiko (JP)**

(73) Assignee: **SMC Kabushiki Kaisha, Tokyo (JP)**

(**) Term: **14 Years**

(21) Appl. No.: **29/121,683**

(22) Filed: **Apr. 12, 2000**

(30) **Foreign Application Priority Data**

Oct. 18, 1999 (JP) 11-28535

(51) LOC (7) Cl. **13-02**

(52) U.S. Cl. **D13/123**
